UNITED STATES PATENT OFFICE.

MEYER HIRSCHTHAL, OF NEW YORK, N. Y., ASSIGNOR OF ONE-THIRD TO FRANK D. HYDE, OF NEW YORK, N. Y.

METHOD AND APPARATUS FOR PROVIDING CONCRETE STRUCTURES.

1,301,561.

Specification of Letters Patent.

Patented Apr. 22, 1919.

Application filed September 13, 1916. Serial No. 119,885.

To all whom it may concern:

Be it known that I, MEYER HIRSCHTHAL, a citizen of the United States, and a resident of New York, in the county of New York and State of New York, have invented a certain new and useful Improvement in Methods and Apparatus for Providing Concrete Structures, of which the following is a specification.

10 My present invention relates to a method and apparatus for providing concrete structures, such as office and commercial buildings, barns, garages, sewers, tunnels, tanks, silos, grain elevators, bridges, trestles, and 15 in fact, practically any structure embodying uprights and floors, or roofs, or both.

The principal object of my invention is 20 to provide structures of the character described, embodying concrete or cementitious material which is placed while in a semi-fluid state and which becomes set in operative relation to permanent supports, such as walls, columns, abutments, piers, etc., to 25 form floors or roofs, by a method and apparatus avoiding the use of temporary posts or uprights, technically known as shores or struts, which are expensive to erect and which impede traffic below the forms for the 30 reinforced concrete before, during, and after the placing of the concrete or cementitious material. This object is accomplished by utilizing permanent uprights to support temporary girders, beams or the like, which in turn support the forms for concrete floor 35 or roof slabs. When there is taken into consideration the fact that forms for floor or roof slabs up to six feet span, must be left intact for approximately six days in summer after placing the concrete, and approxi-

40 mately two weeks in cold weather, the space below the forms, where shores or struts are used, can not be readily utilized for carrying on business, as in buildings, providing a way for traffic, as under bridges, trestles, 45 etc., or for conveying material such as in sewers, culverts, etc. When construction is carried on according to my method and utilizing apparatus constructed and arranged according to my invention, after the permanent 50 uprights have been placed, such as walls, the same may serve a dual function as a means for providing lateral protection for goods in inclement weather, defining a passage or way for traffic, or for confining 55 liquid to a predetermined path of movement.

as in sewers or storing the same as in the case of tanks, while the superstructure, such as floors and roofs are being permanently placed.

Other objects of my invention will appear 60 in the following detailed description, taken in connection with the accompanying drawings, forming a part of this specification, and in which drawings:

Figure 1 is a view partly in elevation and 65 partly in section through a structure, showing one method of construction, parts being broken away and removed, to condense the view.

Fig. 2 is a view partly in plan and partly 70 in horizontal section through the structure shown in Fig. 1, parts being broken away and removed to disclose details.

Fig. 3 is an enlarged central vertical sectional view through an upright of concrete, 75 showing forms, cores, and ledges in operative relation thereto.

Fig. 4 is a view similar to Fig. 3 showing the cores and forms removed and with the ledges detachably secured to the upright, 80 and a temporary supporting member in operative relation to one of the ledges.

Fig. 5 is a view similar to Fig. 3 disclosing a modified form of ledge.

Fig. 6 is a view partly in elevation and 85 partly in central vertical section through the form shown in Fig. 5, but with the concrete forms removed, the ledges detachably secured to the column and a spacer interposed between the temporary member and the 90 ledge.

Fig. 7 is a view similar to Fig. 3, showing the forms removed and with the ledges integral with the uprights.

Fig. 8 is a view partly in elevation and 95 partly in vertical section through a floor slab, and showing ornamental fillers between the ledges of the upright and the under face of the floor slab.

In the drawings, where similar characters 100 refer to similar parts throughout the several views, A designates permanent uprights, in the examples shown, in the form of columns; B ledges carried thereby; C temporary supporting structures to resist transverse 105 stresses, arranged intermediate uprights A supported thereby through the intermediary of ledges B, and in the examples shown, comprises girders D and beams E; F temporary forms for concrete slabs supported upon 110

structures C; G concrete slabs formed upon the temporary forms F; H reinforcement for slabs G where deemed necessary; J a spacer between the structures C and ledges 5 B where deemed necessary; and K a filler interposed between ledge B and slab F after the temporary structure C has been removed.

Referring first to the uprights A, which are to form a permanent part of the structure, they may be in the form of walls, piers, 10 columns, or any other form of upright, and, when made of concrete, may be reinforced as indicated at 9 in Figs. 1 and 2, where the columnar form of upright is disclosed. 15 These uprights may be provided by use of any suitable forms as is indicated in Figs. 3 and 5, in the former of which the ledge B is in the form of a rolled steel or iron angle section, one leg of which serves as a part of 20 the form in the provision of upright A. In Fig. 5 a modified form of ledge is disclosed, in the form of a channel section, the web 12 of which serves as a part of the form in providing the upright A. The ledges may be 25 perforated as at 13, to receive cores 14 which extend transversely through the columns in order to provide ways 15 for bolts 16 clearly shown in Figs. 4 and 6, after the forms 10 and cores 14 have been removed, the bolts 30 16, in combination with nuts 17, providing simple and efficient means for detachably securing the ledges B to the columns, or uprights A. In Fig. 7, the upright A is disclosed as provided with ledges B integral 35 with the main body portion of the uprights and said ledges may or may not be reinforced, depending upon the load coming thereupon, as hereinafter set forth.

If the uprights A are of concrete or embody a cementitious material, no appreciable weight is brought thereupon until the cementitious material has thoroughly set and the upright is not only self-sustaining but also capable of supporting a dead load such 45 as the temporary supporting structures C, temporary forms F and the concrete slabs G with reinforcement H where deemed necessary, which are progressively placed.

Referring now to the temporary supporting structures C, while I have herein shown the same as embodying girders D and beams E, it is to be understood that much will depend upon the span or distance between the spaced uprights A, as to just what form of 50 temporary structure should be provided and the material used, or embodied in said structure. The girder D is shown in the form of an I-shaped rolled steel section, while the beams E are of wood, extending transversely 55 of the girders, the latter being supported by the uprights A through the intermediacy of ledges B. Where the span is great, or where the load is rather excessive, a spacer J clearly shown in Fig. 6 of the drawings, 60 65 may be provided between the supporting

structure and the ledge, and in the example shown, between the girder D and the ledge, the spacer in the example shown, being in the form of juxtaposed complementary wedges. By driving the complementary 70 wedges in opposite directions so that the inclined face of the upper wedge rides upwardly on the inclined face of the lower wedge, the temporary supporting structure C will be raised. If the wedges are moved 75 in counter directions, said structure will be lowered. A spacer J may be provided intermediate the supporting structure at each ledge and facilitates arranging of the upper faces of beams E in the desired plane, 80 and also facilitates dismembering of the temporary structure after it has served its purpose.

After the temporary supporting structure C has been placed in operative relation to 85 the uprights A, the temporary forms for the floor or roof slabs are arranged upon the structure C, said forms, in the example shown, consisting of boards 19 arranged transversely of the beams E, the boards engaging laterally in a manner to prevent loss 90 of cementitious material or concrete which is placed thereupon, to form the floor or roof slab. These boards may be thoroughly tied together so that the pressure of the concrete 95 or the movement of men, machinery, or materials shall not throw them out of place.

After the forms are in place, if reinforcing materials, such as rods, fabricated metal, or tiles, are to be used as a part of the floor 100 slabs, they are placed, and where necessary, securely anchored to the uprights A, the cementitious material of which may be completed to approximately the line 20 prior to the placing of the slab G. This is followed 105 by placing the cementitious material or concrete in a semi-fluid state, upon the forms F, where it is allowed to harden and become self-sustaining before the temporary structures and forms are removed. It is to be observed that, during the assembling of the reinforcement H and the placing of the concrete upon the form F, there is ample head room below the temporary supporting structure C, and that no shores or struts are necessary which would impede traffic or otherwise interfere with movement of material beneath the work being carried on above the forms F. 110 115 120

Where the temporary supporting structure C is of comparatively light material, it may be knocked out from under the completed floor slab but in heavy work, it may be initially lowered by operating the spacers J wherever they occur. 125

While I have herein shown and described the ledges B of rolled steel or iron sections, or of reinforced concrete, it is to be understood that these ledges may be of any suitable material, either permanently or detach- 130

ably carried by the uprights A, and furthermore, if made of material such as concrete, they may be chipped away after they have served their purpose, or in the event it is 5 desired to permit them to remain, an ornamental filler K may be interposed between the ledge B and the under face of the floor or roof slab, giving an ornamental effect and the appearance of a capital as in the case of 10 columns or piers forming the uprights.

Changes in details may be made without departing from the spirit or scope of my invention; but,

I claim:—

- 15 1. The method of erecting cementitious structures, comprising forming permanent spaced columns for the structure, mounting ledges directly and detachably on the columns, supporting removable centering on 20 the ledges, and molding a connecting slab on the centering integral with the columns.
2. In an apparatus for application to per-

manent columns for forming slabs thereon, the combination of ledges detachably supported by the columns, and removable centering carried on the ledges. 25

3. The method of detachably securing ledges to permanent cementitious uprights, comprising erecting a form for the cementitious material including the ledges as a 30 part of the form and placing core rods in the form with the ends projecting through the ledges, and substituting detachable bolts for said core rods after the material is set.

4. In an apparatus for application to permanent columns for forming slabs thereon, the combination of ledges detachably supported by the columns, girders seated upon 35 said ledges, beams engaging across the girders, and forms supported upon said beams. 40

MAYER HIRSCHTHAL.

Witness:

Wm. A. KENT.
